UNITED STATES PATENT OFFICE.

JOSEPH QUINTILE, OF TORONTO, ONTARIO, AND CECIL BRUCE METCALFE, OF GUELPH,
ONTARIO, CANADA.

MUSICAL SETTING OR SCORE.

1,307,147.

Specification of Letters Patent. Patented June 17, 1919.

Application filed August 30, 1918. Serial No. 252,052.

To all whom it may concern:

Be it known that we, JOSEPH QUINTILE, a citizen of the United States of America, and a resident of Toronto, in the county of York and Province of Ontario, Dominion of Canada, and CECIL BRUCE METCALFE, a subject of His Majesty King George V of Great Britain, and a resident of the city of Guelph, in the county of Wellington and Province of Ontario, Dominion of Canada, have invented a new or Improved Musical Setting or Score for Use in Accompanying Moving Pictures and other Such like Purposes, of which the following is a specification.

In the musical accompaniments for moving picture scenes it is frequently necessary to change the temperament and time of the music being played, very rapidly to suit the changes in the character of the pictures thrown on the screen. Heretofore it has been necessary for the musical performer, to turn to another composition in the same or another book, to suit the character of the picture thrown onto the screen, and as it is sometimes very difficult to locate a suitable composition instantaneously, it sometimes necessitates an absolute stoppage or break in the music; and, in cases where there is a plurality of instruments accompanying the pictures it sometimes occasions considerable fumbling around and delay until all are fully in line again in the new air.

The object of our invention is the arrangement on the same sheet of a plurality of staffs, 2, 3, or 4, as the case may be, carrying individual tunes of different character or rhythm, and each one harmonized and complete within itself, as for instance, the top staff may be a piece of hurried, excitable music, and the one beneath a slow, sentimental piece, or a third or fourth may still be added carrying a waltz, or march, etc.

All these tunes are so composed and harmonically arranged that the musician may drop instantaneously from the end of any bar in one piece to the succeeding bar in one of the lower staves, and vice-versa, without interrupting the flow of the music and as often as the mood of the picture requires.

In orchestral arrangements the music of each instrument will also have its individual part to each of the melodies, so that not only can the orchestra change immediately from one to the other as explained above but, the pieces being so composed, the orchestra may be divided into two sections, each section playing a different melody at the same time. Thus at the leader's direction the section playing the excitable music could play loudly while the other section with the sentimental music could be very soft, or the opposite mode could be taken according to the leader's signs and the action on the screen.

I illustrate my invention by means of the accompanying drawing containing three bars each of fast, slow and waltz music respectively as follows: number one hurry, number two plaintive, number three waltz. The music on each one of these staves is interchangeable at the end of any bar. For instance, should the music start on staff number two plaintive and should the musician be notified that an instantaneous change to faster music is desired, he can, at the end of the first bar of the plaintive or slow music-staff number two—instantaneously change to the second bar of the hurry music on staff number one and at the end of the said bar, can just as readily, change back to the third bar of the plaintive or slow music on staff number two without anyone noticing the slightest pause or hesitation or having the slightest idea that the music has been changed. It will readily be seen that this transposition or

change of the character or rhythm of the music, can take place at the end of any bar throughout the entire composition.

We claim:

- 5 A musical setting or score comprising a plurality of musical compositions enharmonically arranged but differing in tone, time and character one below the other upon the same sheet and so printed that the bars
- 10 shall correspond at certain places from the top to the bottom of the sheet so that the performers may change immediately from one melody to another of different character

Copies of this patent may be obtained for five cents each, by addressing the "Commissioner of Patents,
Washington, D. C."

and that the different tunes, enharmonically arranged may be played at the same time by 15 several performers as may be required to accompany moving pictures.

JOSEPH QUINTILE.
